(57) **CLAIM**

We claim the ornamental design for a lid, as described.

DESCRIPTION

FIG. 1 is a front right perspective of a lid showing our new design;

FIG. 2 is a rear left perspective thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top view thereof; and,

FIG. 8 is a bottom view thereof.

The "F" diamond logo forming part of the claimed design is a registered trademark of the Furman University.

The broken lines in the drawings represent unclaimed environmental subject matter and form no part of the claim.
